CARPET.

No. 15,461.

Patented Oct. 14, 1884.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 15,461, dated October 14, 1884.

Application filed August 6, 1884. Term of patent 25 years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The face of the design is traversed by inconspicuous stem-work bearing large prominent lobed leaves and smaller star-shaped flowers both singly and in groups. The ground is filled in with small outline leaf and flower figures, which may, however, be omitted.

I claim—

The design for a carpet, substantially as shown and described.

OTTO HEINIGKE.
